CLAIM

The ornamental design for a valve actuating device, as shown and described.

DESCRIPTION

FIG. 1 is a perspective view of the valve actuating device showing our new design;

FIG. 2 is a rear view thereof;

FIG. 3 is a bottom view thereof;

FIG. 4 is a right side, elevation view thereof;

FIG. 5 is a top plan view thereof;

FIG. 6 is a rear view thereof; and,

FIG. 7 is a left side, elevation view thereof.
